HAIR-WAVING DEVICE

Lucynda I. Fink, Lismore, Iowa

Application October 10, 1950, Serial No. 189,423

7 Claims. (Cl. 132—32)

1

This invention relates to hair wavers.

An object of the present invention is to provide a hair waver which produces a wave simulating in appearance that of professional operators.

Another object of the present invention is to provide a hair waver which is especially adapted for use by inexperienced operators.

A further object of the present invention is to provide a hair waver which is of simple structure and is highly efficient in operation.

Other objects and advantages will become apparent from the following description.

Embodiments of the hair wavers of the present invention are illustrated by way of example in the accompanying drawings, wherein:

Figure 1 is a top plan view of a hair waver of the present invention with the tine on the right side.

Figure 2 is an elevational view with a part broken away, of the hair waver shown in Figure 1 taken from the near side thereof.

Figure 3 is a sectional elevational view taken on the line 3—3 of Figure 1.

Figure 4 is an elevational view of the hair waver shown in Figure 1 taken from the far side thereof.

Figure 5 is a bottom plan view of the hair waver shown in Figure 4.

Figure 6 is a top plan view of the hair waver of Figure 1 but with the tine on the left side.

Figure 7 is a top plan view of another form of the hair waver of the present invention.

Figure 8 is a fragmentary elevational view, in section, of the hair waver with the tine on the right side and the hair waver with the tine on the left side arranged in hair waving position upon a person's head.

Figure 9 is a bottom view of the hair wavers of Figure 8 showing the arrangement of the curved spaced rows of teeth when in hair waving position on the person's scalp.

Referring to Figures 1 to 5 of the drawings, the numeral 1 designates an upstanding bar 1 having a longitudinally curved tine 2 arranged on one side of the bar 1 adjacent the lower end thereof and connected to the bar 1, the tine being adapted to embrace the head. Positioned in face to face confronting relation with respect to the bar 1 is a second upstanding bar 3, the bars 1 and 3 being connected intermediate their ends for movement toward and away from each other. It is to be noted that the lower end of the bar 3 is above and spaced from the lower end of the bar 1. Specifically, the bars 1 and 3 are connected together intermediate their ends for swinging

2

movement about an axis transverse thereof, the axis taking the form of a pin 4 extending loosely through and connected to opposed ears 5, 5' formed on the confronting face of the bar 1 and opposed ears 6, 6' formed on the confronting face of the bar 3. Circumposed about the pin 4 is a coil spring 7, one end of the spring bearing against the confronting face of bar 1 and the other end 7" of the spring bearing against the confronting face of bar 3, the spring 7 biasing the bars 1 and 3 away from each other. Disposed adjacent the lower end of the bar 3 and extending in longitudinal spaced relation with respect to the tine 2 is a support 8, one end of the support being fixedly secured to the bar 3. The support 8 is provided with a longitudinally extending slot 9.

Arranged underneath the support 8 and mounted in the latter for movement toward and away from the other end of the support 8 is a longitudinally curved finger 10, the finger 10 having a series of spaced, vertical, transversely disposed curved rows of teeth 11 projecting from its under face, the rows of teeth being adapted to penetrate the strands of hair. The under face of the finger 10 is convex, Figure 8, with the end adjacent the one end of the support 8 connected to the bar 3 and designated by the numeral 12 Figure 5, being concavely curved and the other end designated by the numeral 13 being convexly curved. The free ends of the curved rows of teeth 11, Figure 8, are substantially flush with the under surface of the tine 2. Projecting from the lower end of the bar 1 adjacent the other side thereof is a foot or leg 14 which is adapted to engage the adjacent portion of the head and cooperate with the tine 2 and finger 10 to conformably position the tine 2 and finger 10 on the head.

Superimposed upon and extending longitudinally of the upper face of the support 8 is a housing 15, the housing being fixedly secured to the upper face of the support and having one end secured to the bar 3. The housing 15 is provided with a slot 16 extending longitudinally from a point spaced from the one end of the housing connected to the bar 3, and terminating at a point spaced from the other end, the slot being in registry with a portion of the slot 9 in the support 8. Positioned within the housing 15 above the slot 9 in the support 8 and mounted in said slot for longitudinal back and forth movement is a saddle 17, the saddle being fixedly connected to the finger 10, intermediate its ends. Arranged longitudinally of the saddle 17 and supported thereon is a coil spring 18 for urging the finger 10 toward the other end of support 8, one end of

said spring being attached to an ear 19 carried by the upper face of the support 8 adjacent the other end thereof. The other end of the spring 18 is secured to an ear 20 projecting from an upstanding lever 21, the lever 21 having the lower end fixedly secured to the finger 10 adjacent to the concavely curved end 13. The lever 21 extends through the slot 9 in the support 8 and the slot 16, and has on the other end a hand actuatable means or finger trip receiving plate 42.

Referring to the form of Figure 6, such form is exactly the same in specific structure as the form illustrated in Figures 1 to 5 inclusive and herein above described, but with the tine 2' arranged transversely of and on the opposite side of the bar 1 adjacent the lower end thereof, such tine being likewise connected to the lower end of the bar 1.

The form of Figure 7 is the same in specific structure as the form depicted in Figures 1 to 5 inclusive and above described in detail, except that the support 8 is provided with a longitudinally curved rod 23 which is positioned adjacent the other side of the bar 1 in parallel spaced relation with respect to the support 8 and which is dependently secured to the support 8 by means of straps 24 and 25, said rod 23 and straps 24 and 25 forming a wing for resting upon the top of a tine of an adjacent hair waver and coacting with said tine to hold the strand of hair therebetween.

In operation, the operator selects the hair waver having the curved tine on the right side or the form of Figures 1 to 5 including the tine 2, presses the bars 1 and 3 toward each other, resulting in the separation of the tine 2 and the support 8 and finger 10 carried thereby, and then while holding the bars 1 and 3 in this pressed position, applies pressure to the finger plate 22 sufficient to effect the complete execution of movement of the finger 10 away from the other end of the support 8. With the parts of the waver being retained in the aforesaid positions, the operator drapes strands of hair over the tine 2 and then positions it upon the head whereupon the bars 1 and 3 are released, causing the draped strands of hair to be gripped between the tine 2 and the curved rows of teeth 11 depending from the convex under surface of the finger 10. At this point the pressure on the finger plate 22 is released, resulting in the execution of the movement of the finger 10 under the action of the spring 13 toward the other end of the support 8. With the execution of the movement of the finger 10 toward the other end of the support 8 the hair anchored about the curved rows of teeth 11 is given the portion of the wave indicated by the letter A in Figure 8. The operator then selects the hair waver having the curved tine and while holding the bars 1 and 3 in this pressed position, applies pressure to the finger plate 22 to effect the complete execution of movement of the finger 10 away from the other end of the support 8, whereupon with the parts of the waver being retained in the aforesaid positions the waver is advanced to a position such that the tine 2' is adjacent to and in side by side relation with respect to the finger 10 of the waver already positioned on the head. At this point further portions of the strands of hair anchored between the rows of teeth 11 of the already positioned waver are draped over the tine 2' and this second waver then positioned on the head. At this point the bars 1 and 3 are released, causing these further draped portions of the hair to be gripped

between the tine 2' and curved rows of teeth 11 depending from the convex under surface of the adjacent finger 10. Upon completion of the return movement of the bars 1 and 3 of the second waver, the pressure on the finger plate 22 on the latter waver is released, resulting in the execution of the movement of the finger 10 under the action of the spring 13 toward the other end of the support 8. With the execution of the movement of the finger 10 of the second waver toward the other end of the support 8, the hair anchored about the curved rows of teeth 11 is given the portion of the wave indicated by the letter B in Figure 8. In the same manner any number of wavers may be placed alternately and in side by side relation until the hair on a head has been completely waved.

I claim:

1. A hair waver comprising an upstanding bar, a longitudinally curved tine arranged on one side of said bar adjacent the lower end thereof and connected to said bar adapted to embrace the head, a second upstanding bar positioned in face to face confronting relation with respect to said first bar and connected intermediate its ends to the latter bar for movement toward and away from each other, a support positioned adjacent the lower end of said second bar and extending in longitudinal spaced relation with respect to said tine and connected at one end to said second bar, a longitudinally curved finger arranged underneath said support and mounted in the latter for movement toward and away from the other end of said support, said finger having a series of spaced vertical transversely curved rows of teeth projecting from its under surface adapted to penetrate strands of hair, an upstanding hand actuatable means exteriorly of said support and having its lower end operatively connected to said finger for moving the latter away from the other end of said support, and spring means arranged longitudinally of and above said support and having one end operatively connected to said finger and having the other end operatively connected to said hand actuatable means intermediate the upper and lower ends of the latter.

2. A hair waver comprising an upstanding bar, a longitudinally curved tine arranged on one side of said bar adjacent the lower end thereof and connected to said bar adapted to embrace the head, a second upstanding bar positioned in face to face confronting relation with respect to said first bar and connected intermediate its ends to the latter bar for movement about an axis transverse of said bars toward and away from each other, a support positioned adjacent the lower end of said second bar and extending in longitudinal spaced relation with respect to said tine and connected at one end to said second bar, a longitudinally curved finger arranged underneath said support and mounted in the latter for movement toward and away from the other end of said support, said finger having a series of spaced vertical transversely curved rows of teeth projecting from its under surface adapted to penetrate strands of hair, an upstanding hand actuatable means exteriorly of said support and having its lower end operatively connected to said finger for moving the latter away from the other end of said support, and spring means arranged longitudinally of and above said support and having one end operatively connected to said finger and having the other end operatively connected to said hand actuatable means intermediate the upper and lower ends of the latter.

3. A hair waver comprising an upstanding bar, a longitudinally curved tine arranged on one side of said bar adjacent the lower end thereof and connected to said bar adapted to embrace the head, a second upstanding bar positioned in face to face confronting relation with respect to said first bar and connected intermediate its ends to the latter bar for movement about an axis transverse of said bars toward and away from each other, a support positioned adjacent the lower end of said second bar and extending in longitudinal spaced relation with respect to said tine and connected at one end to said second bar, spring means operatively connected to said axis and said bars for urging said bars away from each other, a longitudinally curved finger arranged underneath said support and mounted in the latter for movement toward and away from the other end of said support, said finger having a series of spaced vertical transversely curved rows of teeth projecting from its under surface adapted to penetrate strands of hair, an upstanding hand actuatable means exteriorly of said support and having its lower end operatively connected to said finger for moving the latter away from the other end of said support, and a second spring arranged longitudinally of and above said support and having one end operatively connected to said finger and having the other end operatively connected to said hand actuatable means intermediate the upper and lower ends of the latter.

4. A hair waver comprising an upstanding bar, a longitudinally curved tine arranged on one side of said bar adjacent the lower end thereof and connected to said bar adapted to embrace the head, a second upstanding bar positioned in face to face confronting relation with respect to said first bar and connected intermediate its ends to the latter bar for movement about an axis transverse of said bars toward and away from each other, a support positioned adjacent the lower end of said second bar and extending in longitudinal spaced relation with respect to said tine and connected at one end to said second bar, a longitudinally curved finger arranged underneath said support and mounted in the latter for movement toward and away from the other end of said support, a foot positioned adjacent the other side of said first bar and secured to one of said first and second bars adapted to cooperate with said tine and finger to conformably position the latter on the head, said finger having a series of spaced vertical transversely curved rows of teeth projecting from its under surface adapted to penetrate strands of hair, an upstanding hand actuatable means exteriorly of said support and having its lower end operatively connected to said finger for moving the latter away from the other end of said support, and spring means arranged longitudinally of and above said support and having one end operatively connected to said finger and having the other end operatively connected to said hand actuatable means intermediate the upper and lower ends of the latter.

5. A hair waver comprising an upstanding bar, a longitudinally curved tine arranged on one side of said bar adjacent the lower end thereof and connected to said bar adapted to embrace the head, a second upstanding bar positioned in face to face confronting relation with respect to said first bar and connected intermediate its ends to the latter bar for movement about an axis transverse of said bars toward and away from each other, a support positioned adjacent the lower

end of said second bar and extending in longitudinal spaced relation with respect to said tine and connected at one end to said second bar, spring means operatively connected to said axis and said bars for urging said bars away from each other, a longitudinally curved finger arranged underneath said support and mounted in the latter for movement toward and away from the other end of said support, a foot positioned adjacent the other side of said first bar and secured to one of said first and second bars adapted to cooperate with said tine and finger to conformably position the latter on the head, said finger having a series of spaced vertical transversely curved rows of teeth projecting from its under surface adapted to penetrate strands of hair, an upstanding hand actuatable means exteriorly of said support and having its lower end operatively connected to said finger for moving the latter away from the other end of said support, and a second spring means arranged longitudinally of and above said support and having one end operatively connected to said finger and having the other end operatively connected to said hand actuatable means intermediate the upper and lower ends of the latter.

6. A hair waver comprising an upstanding bar, a longitudinally curved tine arranged on one side of said bar adjacent the lower end thereof and connected to said bar adapted to embrace the head, a second upstanding bar positioned in face to face confronting relation with respect to said first bar and connected intermediate its ends to the latter bar for movement about an axis transverse of said bars toward and away from each other, a support positioned adjacent the lower end of said second bar and extending in longitudinal spaced relation with respect to said tine and connected at one end to said second bar, spring means operatively connected to said axis and said bars for urging said bars away from each other, a longitudinally curved finger arranged underneath said support and mounted in the latter for movement toward and away from the other end of said support, the under surface of said finger being convex, a foot positioned adjacent the other side of said first bar and secured to one of said first and second bars adapted to cooperate with said tine and finger to conformably position the latter on the head, said finger having a series of spaced vertical transversely curved rows of teeth projecting from its under surface adapted to penetrate strands of hair, the ends of the curved rows of teeth being flush with the under surface of said tine, an upstanding hand actuatable means exteriorly of said support and having its lower end operatively connected to said finger for moving the latter away from the other end of said support, and a second spring means arranged longitudinally of and above said support and having one end operatively connected to said finger and having the other end operatively connected to said hand actuatable means intermediate the upper and lower ends of the latter.

7. A hair waver comprising an upstanding bar, a longitudinally curved tine arranged on one side of said bar adjacent the lower end thereof and connected to said bar adapted to embrace the head, a second upstanding bar positioned in face to face confronting relation with respect to said first bar and connected intermediate its ends to the latter bar for movement about an axis transverse of said bars toward and away from each other, a support positioned adjacent the lower

end of said second bar and extending in longitudinal spaced relation with respect to said tine and connected at one end to said second bar, spring means operatively connected to said axis and said bars for urging said bars away from each other, a longitudinally curved finger arranged underneath said support and mounted in the latter for movement toward and away from the other end of said support, the under surface of said finger being convex, a foot positioned adjacent the other side of said first bar and secured to one of said first and second bars adapted to cooperate with said tine and finger to conformably position the latter on the head, a wing positioned in parallel spaced relation with respect to said tine and carried by said support, said finger having a series of spaced vertical transversely curved rows of teeth projecting from its under surface adapted to penetrate strands of hair, the ends of the curved rows of teeth being flush with the under surface of said tine,

an upstanding hand actuatable means exteriorly of said support and having its lower end operatively connected to said finger for moving the latter away from the other end of said support, and a second spring means arranged longitudinally of and above said support and having one end operatively connected to said finger and having the other end operatively connected to said hand actuatable means intermediate the upper and lower ends of the latter.
